Inventor:

UNITED STATES PATENT OFFICE.

JOHN KELLY, OF NORFOLK, VIRGINIA, ASSIGNOR TO KELLY BUTTON MACHINE COMPANY, INC., OF NORFOLK, VIRGINIA, A CORPORATION OF VIRGINIA.

BUTTON-SETTING MACHINE.

1,356,772.

Specification of Letters Patent. Patented Oct. 26, 1920.

Application filed October 3, 1914, Serial No. 864,895. Renewed January 12, 1920. Serial No. 350,939.

To all whom it may concern:

Be it known that I, JOHN KELLY, a citizen of the United States, residing at Norfolk, in the county of Norfolk and State of Virginia, have invented certain new and useful Improvements in Button-Setting Machines, of which the following is a specification, reference being had therein to the accompanying drawing.

10 This invention relates to an improvement in button sewing machines, and more particularly to that type of machine wherein a coil of wire is employed and by suitable mechanism the wire is fed automatically 15 through the eye of the button, formed into a staple, forced through the material, and clenched, all during a single operation of the machine.

Heretofore in this art, it has been customary to employ a button raceway or feed tube for conducting the buttons through the staple forming mechanism; to feed the wire transversely through the eye of the button and by a movement of the treadle mechanism or other means, to cause the wire to be severed, formed and clenched, the buttons being held in check by a suitable let-off and released at the proper interval to receive the wire through the eye thereof. Such a 30 machine is illustrated in the patent to Olds and Eklund No. 368419.

The present invention contemplates improvements in features of this early Olds and Eklund patent and may be stated briefly 35 to comprise generally the following features:

First, means for positively grasping and positioning the eye of the button for the reception of the staple wire, as distinguished from machines wherein the feeding and 40 holding instrumentalities are brought into contact with the head or body of the button.

Second, in improved means for operating the wire feed.

Third, to improve the various features of 45 a button setting machine, so that the same will be less complicated than heretofore, strong, durable, and fashioned in a manner to render the machine highly satisfactory and useful in the art of button setting.

50 In the machine illustrated in the accompanying drawings hereinafter described, there are a number of important features which will be referred to in detail, but in addition to illustrating a preferred form of machine there is also illustrated a modified

construction. It is, however, to be understood that the invention and the improved features shown may be modified, changed and altered without departing from the general principles and nature of the invention, 60 but the forms illustrated and described are the best known forms and arrangements at present advised by me.

In the drawings,—

Figure 1 is a side elevation of the machine omitting the lower portion of the pedestal and treadle,

Fig. 2 is a top view of the head of the machine showing the cover plate omitted, and a portion in section,

Fig. 3 is a similar view with the top plate in position,

Fig. 4 is an enlarged side elevation of the head showing parts broken away and viewed from a side opposite from that shown in Fig. 1,

Fig. 5 is a view of the raceway with the side plate removed,

Fig. 6 is a cross section on the line 6—6 of Fig. 2,

Fig. 16 is a detail perspective view of a hardened plate through which the wire passes,

Fig. 17 is a plan view of the rear portion of the machine shown in Fig. 1 illustrating the hopper attachments,

Fig. 18 is a section through the machine at a point intersecting the center of the raceway showing parts in elevation,

Fig. 19 is an enlarged sectional view of the button eye positioning and holding finger with its associated parts,

Fig. 20 is an elevation partly in section

showing the position of the form carrying lever with the eye engaging finger and the cutting and forming die.

Fig. 21 is a side elevation of the head of the machine showing a modified construction of hopper and its attachments, raceway and stop mechanism.

Fig. 21^a is a sectional view of a yielding connection in the stop mechanism,

10 Fig. 22 is a longitudinal section through the head of the machine, as shown in Fig. 21, parts being omitted,

Fig. 23 is a side elevation,

Fig. 24 is a plan view,

15 Fig. 25 is a cross section through a modified form of button raceway,

Fig. 26 is a plan view of the construction of head shown in Fig. 21 with the stop mechanism omitted, and

20 Fig. 27 is a front elevation of the construction shown in Fig. 26, taken in the rear of the clenching anvil.

A is the hollow stand, which, as is usual, is carried by supporting feet, not shown,

25 and through which passes the operating rod A' to be connected with a foot treadle and surrounded by a spring normally tending to move the rod upward, as is usual. On the top of the standard A is the tray A² of

30 any convenient form. Removably secured to the tray by bolts and butterfly nuts b is the head of the machine comprising conveniently a casting having a bottom portion b', through which the aforesaid bolts

35 pass and from which extend upward the supporting parts b², b³, the latter being divided vertically into two portions forming an intermediate space therebetween. On the upright b² is positioned the clenching

40 die b of the usual form. This upright or die carrying part is projected outwardly to form a space between the die and the body part of the head casting. The head base plate B is arranged at an incline on and projects laterally beyond the upright portions and constitutes the support and carrying portion for the operative parts of the machine.

45 As shown in Fig. 2, the base B is offset laterally at one side to form a housing 50 for the wire feed mechanism, presently to be described, and is provided with a vertical chambered parts b⁵, in which is pivotally supported a tilting lever C, which carries the combined button feed and holder

55 as well as the staple former. On the left hand edge of the head casting there is an upstanding flange b⁶, while a complementary flange portion b⁷ is arranged diametrically opposite thereto. Between these flanges on

60 opposite sides of the chambered portion b⁵ is formed a guideway for the staple driver D and the wire cutting and staple forming dies E, which in turn are backed up at their lower end portions by the removable hardened plates F and F', the latter having a

perforation f therein, through which the staple forming wire is passed. This plate F' is conveniently provided with a curved recess f' in which fits a pin f² extending from the side guide of the base. The plate is conveniently provided with two holes or perforations f and being loose and symmetrically formed, by turning the plate one half round the opposite hole, can be employed for threading the wire through. The perforations are preferably arranged diagonally opposite to each other and the advantages of this construction lies in the fact that if by constant use the cutting edges of the plate at the perforations become worn or broken, the other perforated part can be used. The plate F is by preference backed up with a spring F² contained in a housing F³ on the side of the base flange and which engages a positioning pin F⁴ on the plate. This insures a proper contact between the plate F' and the cutting and forming die E during the operation of cutting the staple wire. Slidably supported on the top surface of the head base B is the substantially U-shaped yoke member G, the arms g, g' of which carry between them the spring pressed rod G', the lower end of which extends through and below the end of the arm g. This yoke is provided with ears g² on its lower portion projecting through an opening in the base plate and to which is pivotally secured an operating link h of the bell crank H pivoted between the rear uprights of the head, and to the forward arm of which is connected the operating bar A' of the machine. By pressing on the treadle, the yoke member is caused to move downward.

The wire cutting and forming die E is conveniently in the form of a hardened steel block having a central longitudinal channel in which slidably moves the staple driver D, the same fitting closely. The block E is provided with a narrow wire receiving groove at the upper edge of its lower end and the inner faces of the walls of the channel part are grooved slightly to receive projections d on the staple driver. Extending across the rear part of the block is a pin e', over which the staple driver passes, there being formed in the latter an elongated groove or cut out portion d', so positioned that the staple driver will have a limited movement independent of the cutting and forming die block. The staple driver is also provided with a notch d³ fashioned to fit over the arm g of the yoke G, so that the movement of the yoke will cause a corresponding movement of the staple driver.

Mounted on the upper face of the yoke is a pivoted block J, having a shoulder part j arranged normally in the path of the end of the wire cutting and forming die, as shown in Fig. 2. This block J has a cam groove j' therein, the walls of which engage

with a fixed pin j^2 during the downward movement of the yoke, and thus causes the block to turn on its pivot from engagement with the end of the wire cutting and forming die block E.

On the upper end of the yoke G is a pivoted arm G^2 , having its outer end forked to embrace the spring actuated rod G' . K represents the pivoted wire feed lever supported on the head casting in the recess, having an upper arm k lying above the pivoted arm or member G^2 . This wire feed is of the conventional type, having a wire feeding dog k' at its lower end, and is carried inward by the movement of the yoke back to its normal position, and to be forced outward by forming on the lower end of the block J an outstanding rounded end portion J'. This part engages the side of the swinging feed lever carrying the same outward for grasping the wire for the feeding action. The usual stop pawl or feed member K^2 is employed for retaining the wire against backward movement, when the feed lever is moved. The wire is conveniently coiled on a spindle connected with an arm L extending from the head of the machine.

In the machine heretofore produced, it has been customary to feed the buttons directly to the point of the wire feed by engaging the head of the button. This is objectionable, as in many instances the heads are bruised, the mechanical parts being positive. In instances where glass headed buttons are employed, they are often broken. I have conceived a means of operating the button feed by engaging the shanks only thereof in a positive manner, which will not only position the shanks, but which will positively hold them in position during the wire threading interval. With this end in view, I have provided the arm C with a special button eye-grasping and positioning member as shown in Figs. 11, 12, 13 and 14. The body part of the arm C is of the conventional type, having the upstanding operating part c at its rear, with which the lower arm g of the yoke G normally engages the upper edge of this arm, being beveled as shown in Figs. 18 and 20. As the yoke is positioned normally by the operating spring of the treadle, the arm C is rocked, carrying the lower end upward into the path of the button. The forward end of the rocking arm C is slotted as at c' back of the former part C'. In this chamber or slot is positioned the grasping or clamping finger C ^{2} , the same being mounted on the shaft c^2 pivotally supported in the sides of the slotted parts of the arm. The finger has a square hole therein, with which a squared part of the shaft, as at c^4 engages, so that upon a movement of the shaft, the finger is caused to move correspondingly. The end of the finger projects upwardly in the rear of the staple former and is rocked through the instrumentality of a crank or disk C ^{3} , eccentrically keyed to or secured on the outer end of said finger supporting shaft. This crank or disk is so positioned that when the parts are in normal position, it will lie in the path of the outside portion of the wire cutting and forming die block E. This outside portion of the block E is cut away on a gradual curve, as at E ^{4} , so that it engages the disk C ^{3} above the center plane thereof, and depresses the same, thus rocking the finger, causing it to release the button eye and to recede below the plane of the incoming button shank. The finger is retained in this position during the remainder of the stroke of the machine, while the wire staple is being formed, and thereupon the staple driver advances. The upturned end of the rocking arm C, escaping the upper end of the staple driver, permits the lower end and the finger to drop down out of the way of the moving staple driver and staple forming die, in which position the finger may still be held retracted by the contact of the under surface of the block E and the eccentrically mounted disk. A spiral spring C ^{5} is employed, which is connected at one end to a projection c^5 on the under edge of the swinging arm C, its forward end being connected to a tooth on the lower end of the finger. This spring normally tends to set the upright end of the finger forward, as shown in Fig. 18, and is tensioned by the rocking of the eccentric disk. Upon the retreat of the staple former and wire cutting and forming die, the bar C is rocked into position, throwing the forward or former end upward, and as soon as the block E leaves the eccentric disk, the finger will be in position back of the eye of the next succeeding button, and by the spring is forced into position to advance, position and clamp the eye of the button for receiving the next wire length for the staple therefor.

The head base is, as stated, arranged at a slight angle, and owing to the flat characteristic of its upper face, the parts thereon supported are maintained on substantially the same plane. The surrounding flanges of the base casting are of a height to coincide with the upper faces of the sliding staple driver, the upper faces of the sliding wire cutter and former block, and the pivoted block J. The yoke G is provided with parts that are extended outward in line with the upper faces of the aforementioned parts and the swinging feed lever is provided with a boss, also having its edge coinciding with the plane of the flanges. This fact is mentioned, for the reason that the cover plate M is designed to fit over the entire surface of the base casting of the head and to serve

as a means for holding the parts in their operable position. The cover plate M is provided on its upper face with an obliquely arranged rib m having an inclined groove m' therein of a width to accommodate a button eye. The groove extends from end to end of the rib, while the cover plate at the forward end of the rib is cut away to form a continuation of the guiding button 10 surface represented by the top of the rib, all as shown at m^2 . Conveniently, the lower end of the button guiding surface may be reinforced by a steel plate, as shown at m^3 . Owing to the inclination of the head and the 15 greater inclination of the button carrying surface of the rib, buttons placed on the rib will naturally by gravity slide down to the lower end thereof, and when at the extreme end of the guiding surface of the rib, the 20 eyes will be below the plane of the cover plate, and between the feeding and clamping finger and the former of the rocking lever C. It is expedient to inclose the buttons, and thereby, in conjunction with the rib, 25 form a raceway for the buttons. This is accomplished by providing a movable cap N of substantially U-shape in cross section and designed to span the top of the rib. This plate is, by preference, provided with 30 a series of elongated slots in its upper surface, through which a suitable pin or implement can be placed to dislodge any button or obstruction that might clog the raceway. The lower end of the cap N is carried 35 down to a point slightly in advance of the lower forward end of the button guiding surface of the rib, and its extension in the cap is cut away slightly, near its lower end, so that an implement may be inserted there- 40 in to relieve any congestion that may occur at the lower end of the button raceway. N' represents a stop finger pivotally supported 45 on the bracket n' on the cap N, and spring pressed so that its forward hooked end will normally project in front of the raceway. The rear portion of this member is formed 50 with a finger piece n^2 so that, by applying pressure thereto, the stop or hooked end may be elevated to allow the buttons to freely pass from the reservoir when the former is lowered.

In many instances, it is desirable to use buttons with different size heads, and to provide for this requirement, the cap N is 55 made adjustable vertically, to increase the distance between its crown and the guiding surface of the rib. To accomplish this purpose, one side of the cap is provided with two inclined depending parts N^2 , N^3 which 60 normally are engaged by projections N^4 , N^5 on a sliding plate N^6 . Rigidly secured to the side of the rib is a plate N^7 , having journaled therein a shaft n^7 carrying a small pinion n^8 , which meshes with a rack n^9 on

the sliding adjusting plate. The plate N^6 is 65 normally held in position by two outstanding pins n^4 working in elongated slots n^5 in the plate. On the outer face of the inclined portions of the cap are formed ribs n^{10} , which fit in grooves n^{11} in the plate N^7 , so 70 that the cap may be adjusted vertically and still maintained in its proper position. To retract the cap or hold it down, suitable pins n^{12} and n^{13} , are projected out therefrom and are engaged by coil springs n^{14} attached to 75 the side plate N^7 . By turning the pinion through a thumb nut connected therewith, the slide is moved rearward, elevating the cap of the raceway against the tension of the springs and maintaining it in that position. In the elevated position, the raceway will accommodate large headed buttons, and when in its lowered position, caused by the reverse movement of the parts, the raceway 80 will accommodate buttons having relatively 85 smaller heads, as will be obvious. By this arrangement of an adjustable cap for the raceway, the necessity of changing the button tubes or raceways, is avoided by a very 90 easily adjustable construction provided for rendering the machine operable with different size buttons.

It is necessary in button setting machines that the operator have access to the wire 95 feeding jaws when fresh wire is to be supplied, or when the machine is to be started. This requires an exposure of these parts, which exposure heretofore has been objectionable, owing to the fact that the parts are rough and provided with sharp edges, 100 which injure the stock. To avoid this objection, the head is cut back somewhat and attached to the cover plate M is a hinged guard and cover O. This cover has a depending side o, which projects in front of 105 the wire feeders and forms a smooth even guide wall for the channel or space between, and into which the stock is fed. When it is desired to get access to the wire feed it is only necessary to raise this hinged cover, 110 which will expose the entire working parts of the wire feed. The cover O extends from a point substantially adjacent the center of the cover plate M to the outer edge.

Conveniently, on the side of the head is 115 a projecting box-like structure B⁵, in which is placed a register of any desired type B⁶. This register has its operating wheel projected into the path of a laterally extending pin G⁶ on the upper end of the yoke G, 120 so that each operation of the machine is recorded. The cover plate M has a slot therein immediately above the register, as shown in Fig. 3.

For supplying buttons to the raceway, a 125 bracket P is removably secured to the back of the head by suitable screws, and this bracket is provided at its outer end with a

ball socket p having contractible sides operable by a thumb screw p' . This extension carries what will be termed herein, twin hoppers Q supported on opposite sides of a central partition from the lower portion of which extends a stem Q' having a ball Q^2 on its lower end fitting said socket p . This enables the hopper to be tilted back or to be turned in either direction, as conditions require. When it is desired to place buttons in the raceway by hand the hopper is tilted back, and when it is desired to conduct the buttons from the hopper into the raceway, the same is tilted forward until its discharge end R is in line with the button raceway. While in this position, a thumb screw r enters a bifurcated slot r' on the plate N' and by turning the thumb screw, is thereby locked firmly in position with the discharge of the hopper directly in line with the raceway. The other member of the pair of hoppers is similarly furnished with a securing device, so that by turning the hopper half round, a companion hopper can be used. One hopper may contain buttons of one color, and the other of another, and one hopper may contain buttons of one size head, and the other of another size head.

The specific construction of the hopper is disclosed in my Patent No. 1128456 dated February 16, 1915, and need not herein be described. To operate the button distributors of the hopper, a shaft S is supported at the rear of the head having a crank arm s connected with a link s' to the operating bell crank of the machine. The other end of the shaft S is provided with a crank arm s^2 carrying a link S^2 . This link is bifurcated at its outer end and has a spring actuated clip s^3 thereon extending over the open end of the bifurcation. On the button agitator shaft of the hopper is placed a ratchet wheel T , with which a spring actuated pawl T' engages. This pawl is pivotally supported on a disk T^2 mounted on a distributor shaft, and which has an arm T^3 extending therefrom provided with a wrist pin t . This wrist pin is adapted to fit on the bifurcated pin of the link S^2 , so that as the shaft S is rotated or oscillated, the pawl will have a to and fro movement around the ratchet wheel, and cause a step by step movement of the ratchet wheel and thereby cause the button distributor to rotate. Other means can be employed in lieu of this pawl and ratchet construction. By forming the detachable connection between the wrist pin and the link S^2 , when it is desired to turn the hopper it is only necessary to separate the two parts, which can be quickly done, and the link S^2 coupled to the wrist pin of the companion hopper actuator. It will be noted that when one hopper is in operation, the outlet or dis-

charge mouth of the opposite hopper is in an elevated position, so that the buttons will not escape therefrom.

In operation, the shoe upper is placed in position between the former block and staple driver and the clenching die, buttons having been fed into the button raceway, and the wire feed being adjusted so that the wire will be fed through the eye of the button. Pressure is brought to bear on the treadle, rocking the bell crank, forcing the yoke G downward, which in turn, through the pivoted block J carries the forming and cutting block E downward in its guide between the steel plates, throwing back the grasping finger of the lever C , which will assume a position back of the eye of the advance button and positioning the wire feeding lever outward to grasp the wire for feeding purposes. No button has been attached or staple formed in this operation. Upon the subsequent operation, the wire is fed through the button eye, which is held tightly by the holding finger, a staple formed, driven through the leather of the shoe and clenched by the clenching die. Upon the return movement, the machine is in position for setting the next button, and so on, upon a single stroke. In the return of the parts, the laterally projecting arm on the yoke engages the hooked end of the wire feeding lever, cushioning the movement of the parts and yieldingly driving the lever forward to feed the wire, while the downward stroke through the projection on the block E forces the wire feeding lever outward. The operation of the feeding and holding finger through the movement of the block E has been heretofore described.

As a modification of the construction thus far described, there is shown in Figs. 21, 23, 24 and 26 a button raceway U of tubular formation, as shown particularly in Figs. 23 and 24, the upper edge or crown of the tube being split or open longitudinally to form a space into which is projected a gaging bar U' . This gaging bar is supported for vertical movement by laterally extending arms u pivotally secured to lugs on the side of the raceway tube. Projecting outwardly from the outer face of the gage bar is an adjusting nut u' mounted on a pivot eccentrically, so that by turning the nut the gage bar will be held in different positions of adjustment with relation to the top of the buttons passing through the tube. This nut may be conveniently numbered on its side faces, and owing to the eccentric mounting, will, manifestly, hold the bar by having the lower face of the nut engage the edge portion of the tube. This form of adjustable button race is illustrated as indicating the general breadth of the improvement, and

may be in some instances found very satisfactory.

In Figs. 21 and 26, there is shown an arrangement of hopper with its associated actuating means quite similar to that of my aforementioned application, differing therefrom only in the fact that the button race or tube which is a fixed part of the machine, and the outlet from the hopper 5 chambers are arranged to be locked directly together, in any convenient manner, when properly adjusted. The special means, as shown in Figs. 21 and 26, is that of two oppositely disposed angle arms V, on the outlets having inturned ends between which spring pressed dogs v carried by or secured 10 to the stationary button raceway engage the ends locking the parts.

In machines of this character, it has been 20 found convenient in some cases to provide a wire feed stop to prevent the operation of the machine, in the absence of a button. With this end in view, I have provided, conveniently, as in Fig. 21, a mechanism 25 consisting of a pivoted locking arm W, having an upturned end w designed to engage back of the reciprocating parts of the forming mechanism of the button fastening head. This locking bar is normally held 30 in inoperative position by the main spring of the machine, through a lug w' engaging the upper end wall of an elongated slot in a sliding arm W'. The end of this arm is cup-shaped and carries a cylindrical housing in which is located a coil spring w². The cylindrical part of the arm W' is guided in a suitable guide bracket W² on the side of the machine. W³ represents a hook shaped arm having its lower end extending 40 into the said cylinder and capped with a suitable plate upon which the coil spring rests, the upper end of the spring abutting the inturned edges of the cylinder part. The opposite or free end of the arm 45 W³ is fashioned to fit the crown of the button head and is located directly above the place where the lowermost button in the button raceway is positioned for receiving the wire. The locking arm W is pivotally 50 and slidably secured to the curved arm W³, as shown.

The operation of this feature of the machine is as follows:

A button being absent from the lower 55 end of the raceway, movement on the treadle carries the arm W³ downward, and owing to the spring connection between the arm W' and W³, the pressure is yielding. This movement continues until the end of 60 arm W³ reaches a position of the button, and finding no button, continues in its descent. This will rock the locking arm into position back of the yoke of the button setting mechanism and prevent its return 65 to normal position. When a button is pres-

ent, the downward movement of the arm W³ is prevented beyond the button top, and the locking arm is consequently rocked only a portion of its distance and does not project beyond the yoke. It is to be understood that other forms of stop mechanism may be employed.

I have not particularly described the former die, as that is of substantially the usual construction. In the modified form, 75 the spring pressed finger N² for retaining the buttons in the runway may be located at the side, as shown in Figs. 21, 23, 24 and 26.

In reference to the hopper actuating mechanism, it will be understood that by 80 uncoupling the link S² from the arm T³, which can be very easily and readily done, the arm T³ can be actuated by hand backward and forward, so as to load the usual chute within the hopper. Heretofore, it 85 has been necessary to open the hopper door or lid and turn the agitator or feeder within the hopper by hand when conditions require, which resulted repeatedly in buttons being thrown out of the machine. This is 90 objectionable and the objection is entirely overcome by the construction shown.

The invention appertaining to the button race-way is not herein claimed but is made 95 the subject matter of concurrently pending applications Nos. 54365, filed October 6, 1915 and 134384, filed December 1, 1916.

Having thus described the invention, what is claimed as new and desired to be secured by Letters Patent is:

1. In a button setting machine, the combination with staple forming and driving mechanism, means for operating the same, and a wire feed, of means for engaging a button eye on opposite sides and clamping 105 the same in position to receive the staple wire therethrough.

2. In a button setting machine, the combination with staple forming and driving mechanism, and means for operating the 110 same, of a wire feed, and means engaging the opposite edges of the button eye for clamping and retaining the same in position for the wire being fed.

3. In a button setting machine, the combination with staple forming and driving instrumentalities, means for operating the same and a wire feed, of means for engaging the opposite parts of the button eye for clamping the same in position for receiving 120 the wire being fed, said means comprising a spring-pressed member.

4. In a button setting machine, the combination with a staple forming and driving mechanism, of means for operating the same, 125 a wire feed, a former, and clamping means carried by the former for engaging a button eye to retain the same in position to receive the staple wire, said retaining means clamping only the eye portion of the button.

5. In a button setting machine, the combination of button setting instrumentalities, means for operating the same, a wire feed, means for operating on the rear of the button eye for properly positioning the same comprising a finger member, a spring for operating the finger in one direction to clamp the button eye, and means operated by said setting mechanism for moving the finger against the tension of the spring. 10
6. In a button setting machine, the combination with a pivoted former bar having a staple form thereon, of means carried by the bar for engaging the button eye only to position the same to receive the staple wire. 15
7. In a button setting machine, a combination with setting instrumentalities and a wire feed, of a pivoted form carrying bar and means for clamping a positioned button in place to receive the wire feed adapted to have a clamping engagement with only the button eye. 20
8. In a button setting machine, the combination with button setting instrumentalities, and a wire feed, of a staple-form carrying bar and a button positioning means movably supported on said bar with means for operating said button positioning means. 25
9. In a button setting machine, the combination with setting instrumentalities and a wire feed, of a pivoted form-carrying bar, a spring pressed finger carried by the bar having its upper end arranged to project into the line of the eyes of the buttons fed to the machine, and a crank projection associated with said finger arranged in line with the button setting instrumentalities for moving the finger out of button eye engaging position. 30
10. In a button setting machine, the combination with setting instrumentalities comprising a cutting and forming die, of a pivoted form-carrying lever, a button engaging member pivotally supported on said form carrying member, and means engaged by the forming die during its downward stroke for removing said button engaging member from button engaging position. 40
11. In a button setting machine, the combination with a reciprocating forming die, a staple driver and a wire feed, of a form-carrying lever, a button eye engaging finger pivotally mounted on the lever, a curved crank member associated with the finger, and means on the die for engaging the crank to rock the finger in one direction. 50
12. In a button setting machine, the combination with a reciprocating forming die, a staple driver and a wire feed, of a form carrying lever, a spring actuated finger pivotally mounted on the lever, a curved crank member associated with the finger, and means on the die for engaging the crank to rock the finger in one direction. 60
13. In a button setting machine, the combination with setting instrumentalities and a wire feed, of a movable staple former, a finger pivotally supported thereby in the rear of the former, a spring for operating the finger, and means for moving the finger in opposition to the spring. 65
14. In a button setting machine, the combination with setting instrumentalities and a wire feed, of a form-carrying bar having a recess in its end, a movable button engaging member pivoted in the recess, and means associated with the button engaging member for moving the same upon the operation of the machine. 70
15. In a button setting machine of the character described, the combination with setting instrumentalities and a wire feed of a slotted form carrying member, and a pivoted finger for grasping the button eye carried by said member. 80
16. In a button setting machine, the combination with a setting instrumentality, of a form carrying member, a finger pivoted therein arranged to project into the path of the buttons, a shaft on which the finger is pivoted, a spring for actuating the finger in one direction, and an eccentrically mounted disk secured on the end of the shaft for operating the finger and tensioning the spring upon the movement of the setting instrumentalities. 85
17. In a button setting machine, the combination with a button setting mechanism, of wire feeding mechanism, the latter comprising a swinging arm, means for moving the arm in one direction, and means pivotally mounted on the machine independently of said first mentioned means and remotely positioned therefrom for engaging the arm intermediate its ends and during the operation of the machine moving the arm in a direction opposite to the direction of movement imparted to said arm by the first mentioned means. 90
18. In a button setting machine, the combination with setting instrumentalities and a wire feed, comprising a swinging arm, of a pivoted block carried by the setting instrumentalities, means for moving the block, and a projection on the block for engaging said swinging arm and for moving the same outwardly, the said arm being moved inwardly by the setting instrumentalities upon a return movement thereof. 100
19. In a button setting machine, the combination with forming and setting instrumentalities comprising a pivoted elongated block, of a swinging wire feeding arm, means for causing the arm to move in a feeding direction, and means on the block for engaging the arm intermediate its ends for moving the same loosely over the wire to be fed. 110
20. In a button setting machine, the combination with forming and setting instrumentalities comprising a pivoted elongated block, of a swinging wire feeding arm, means for causing the arm to move in a feeding direction, and means on the block for engaging the arm intermediate its ends for moving the same loosely over the wire to be fed. 120
21. In a button setting machine, the combination with forming and setting instrumentalities comprising a pivoted elongated block, of a swinging wire feeding arm, means for causing the arm to move in a feeding direction, and means on the block for engaging the arm intermediate its ends for moving the same loosely over the wire to be fed. 125

20. In a button setting machine, the combination with setting instrumentalities and a wire feed, of a pivoted member having an extended curved part for engaging the wire feed and moving the same in one direction. 65
21. In a button setting machine, the combination with wire feeding, staple cutting and button setting instrumentalities, of a cover plate for the same having a cut out portion adjacent the wire feeding means, and a hinged cover for said cut out portion having a work guiding edge. 70
22. In a button setting machine, the combination with setting instrumentalities and a wire feed, of a cover plate having a cut out portion over the wire feed, and a hinged cover for said cut out portion having a depending work guiding flange, for the purposes specified. 75
23. In a button setting machine, a wire feeding mechanism, and a hinged cover for the feeding mechanism having a forward edge part fashioned to serve as a guide for the article to which the buttons are to be applied. 80
24. In a machine of the class described, a movable wire feed member, a reciprocally movable plunger, a cam-dog carried by said plunger for movements therewith, and means operable, during a predetermined portion of a movement of said plunger, to move said cam dog relative to the plunger and to cause it to engage and impart a predetermined movement to said member. 85
25. In a machine of the class described, a movable wire feed member, a reciprocally movable plunger, a wire shaping member, a single element carried by said plunger for movements therewith and operable to coat with and move said shaping member during a portion of the movement of said plunger, and means operable during a predetermined portion of a movement of said plunger to move said element relative to the plunger to disengage the shaping member and to engage and impart a predetermined movement to said wire feed member. 90
26. In a machine of the class described, a reciprocally movable plunger, separate wire feed and shaping members movable one at an angle to the other, and a single means pivotally carried by said plunger and automatically operable, during different portions of a movement of said plunger, to impart respective movements to said members from the plunger. 95
27. In a machine of the class described, a frame, a plunger, a wire feed member and a wire shaping member, each mounted for relative movements on said frame, a cam-dog carried by the plunger and adapted to engage said shaping member during a portion of a movement of the plunger to impart movement from one to the other thereof, and means operable, at a predetermined point in a movement of the plunger, to release the dog from engagement with said shaping member and to move it to engage and impart a predetermined movement to said feed member. 100
28. In a button setting machine, the combination with staple forming and driving mechanisms and a wire feed, of adjustable means for engaging a button eye and holding the same in position to receive the staple wire, said means comprising a pivoted member mounted below the staple forming and driving mechanisms and carrying a movable latch. 105
29. In a button setting machine, the combination with staple forming and driving means comprising reciprocating members and a wire feed, of adjustable means for engaging opposite sides of a button eye and forcibly holding the same in position to receive the staple wire, the reciprocating staple former having a part thereof beveled for moving said adjustable button eye engaging means. 110
30. In a button setting machine, the combination with staple forming and driving devices, the staple former having spaced portions, of means for engaging opposite sides of and forcibly holding a button eye in position to receive a staple wire, the staple former being fashioned to engage and move the button eye holding means as the staple former nears the end of its stroke. 115
31. In a button setting machine, the combination with a staple former having spaced portions and provided with a beveled part, of a driver disposed between said spaced portions, a wire feed, and a movable button engaging and forcibly holding member adapted to support a button eye by engagement with opposite parts thereof to receive the staple wire, the said member being moved by the engagement of the beveled part of the staple former with a portion carried by said member as the former nears the end of its stroke. 120
32. In a button setting machine, the combination with setting instrumentalities and a wire feed, of a movable staple former having a bifurcated end and an upturned portion, a finger pivotally supported at the bifurcated end of the former for engaging and holding with the upturned part thereof a button eye, and means for moving the finger to release the positioned button. 125
33. In a button setting machine, the combination with setting instrumentalities and a wire feed, of a movable staple former having a bifurcated end and a lever having an upturned portion, a finger pivotally supported at the bifurcated end of the lever for engaging and holding with the upturned part thereof a button eye, and means for

moving the finger to release the positioned button, said means comprising a part connected with the finger and adapted to be engaged by the staple former.

34. In a button setting machine, the combination with a reciprocating forming die, a staple driver and a wire feed, of a lever having a projecting portion, a spring actuated button clamping finger mounted on said lever, and a crank member operatively associated with the finger and adapted to be shifted by the die to rock the finger upon a movement thereof in one direction.

35. In a button setting machine, the combination with a reciprocating forming die having a beveled surface, of a staple driver and a wire feed, a lever, a finger pivotally mounted on said lever, and a part connected with the finger and adapted to be engaged by the beveled portion of the forming die to rock the same upon a movement of the forming die in one direction.

36. In a button setting machine, the combination with staple driving and forming instrumentalities, of operating means therefor, a wire feed, means for supporting a button to receive the staple wire, and means operating automatically for preventing the operation of the driving and setting instrumentalities if a button is not in position to receive the staple wire.

37. In a button setting machine, the combination with staple driving and setting instrumentalities and operating means therefor, of a wire feed, means for supporting a button to receive the staple wire, and means acting automatically and having a resilient connection with the operating means for preventing the operation of the setting and forming instrumentalities if a button is not positioned to receive the staple wire.

38. In a button setting machine, the combination with staple forming and driving instrumentalities, of operating means therefor, a wire feed, means for supporting a button to receive the staple wire, a stopping device for the driving and forming instrumentalities and a member operable by the staple setting and forming instrumentalities and adapted to actuate the stopping device if button is not positioned to receive the staple wire.

39. In a button setting machine, the combination with staple driving and forming instrumentalities, of operating means therefor, a wire feed, means for supporting a button to receive the staple wire, a member operable by the staple forming and driving instrumentalities and having a yieldable connection therewith, and a pivoted arm cooperating with said member and adapted to engage and lock said setting and driving instrumentalities upon an extreme movement thereof when a button is not positioned to receive the staple wire.

40. In a button setting machine, the combination with staple driving and forming instrumentalities, of operating means therefor and a wire feed, means for supporting a button to receive the staple wire, and means having a yieldable connection with said operating means for preventing the operation of the staple forming and driving instrumentalities if a button is not positioned to receive a staple wire. 70 75

41. In a button setting machine, the combination with staple driving and forming instrumentalities, of operating means therefor and a wire feed, means for supporting a button to receive the staple wire, and means 80 having a yieldable connection with said operating means for preventing the operation of the staple forming and driving instrumentalities if a button is not positioned to receive a staple wire, said means including 85 a rocking lever having an offset locking portion.

42. In a machine of the class described, a movable wire feed member, a plunger, a pivoted dog carried by said plunger for 90 movement therewith, and an upstanding part disposed in the path of movement of said dog and adapted to engage the cam surface thereof to shift the dog and impart 95 a complementary movement through the wire feed, substantially as described.

43. In a machine of the class described, a movable wire feed member, a reciprocating plunger, a dog pivoted on said plunger for movement therewith, and a fixed part carried by the machine and disposed within the path of movement of said dog for engaging the dog and shifting the same to impart a predetermined movement to the wire feed 100 member. 105

44. In a machine of the class described, a movable wire feed member, a plunger, a pivoted dog having an irregular edge carried by said plunger for movement therewith, and stationary means carried by the machine and disposed within the path of the dog for engaging the irregular edge thereof to move the same to impart a corresponding movement to the wire feed member. 110 115

45. In a machine of the class described, a movable wire feed member, a plunger, a pivoted dog having an irregular edge carried by said plunger for movement therewith, and stationary means carried by the machine and disposed within the path of the dog for engaging the irregular edge thereof to move the same to impart a corresponding movement to the wire feed member, the said wire feed member being adapted to be returned to its normal position upon the return stroke of the plunger. 120 125

46. In a button setting machine, the combination with staple forming means and a wire feed, of means for supporting a button 130

to receive the staple wire to be acted upon by the staple forming means when a button is properly positioned, and means acting automatically for preventing the operation 5 of the forming mechanism of the machine if a button is not positioned on the button support.

In testimony whereof I hereunto affix my signature in the presence of two witnesses.

JOHN KELLY.
